UNITED STATES PATENT OFFICE.

WILLIAM V. ROBINSON, OF LANSING, MICHIGAN.

STOVE.

1,211,236.

Specification of Letters Patent. Patented Jan. 2, 1917.

Application filed April 24, 1914. Serial No. 834,092.

To all whom it may concern:

Be it known that I, WILLIAM V. ROBINSON, a citizen of the United States of America, residing at Lansing, in the county of 5 Ingham and State of Michigan, have invented certain new and useful Improvements in Stoves, of which the following is a specification, reference being had therein to the accompanying drawings.

10 My invention relates to stoves, and resides in the provision of an underfeed heating stove which will effect an efficient burning of the products of combustion; in a novel construction of grating or bottom for a fire- 15 pot; and in certain details of construction as will more fully hereinafter appear.

In the drawings, Figure 1 is a perspective view of a stove embodying the invention; Fig. 2 is a vertical, central section there- 20 through; Fig. 3 is a section on the line $x-x$ of Fig. 2; and Fig. 4 is a perspective view of the under side of the grate.

25 A designates the fire-pot of the stove, B the ash pit suitably mounted upon a base C, and D is the drum extending upwardly 25 above the fire-pot.

30 E is the fuel inlet formed by a forwardly-extending enlargement of the fire-pot, preferably integral therewith, and F is a door or closure for the outer end of the fuel inlet. Secured to the drum is a sectional cast ring 35 G having the portion intermediate its ends dished inwardly, forming a chamber H intermediate the portion H' of the stove wall and the ring. In the structure shown, the ring G has an upwardly extending annular flange I at its upper end attached to the drum as by rivets I', while the lower edge 40 rests against the upper portion of the fire- pot preferably below the top edge of the fire-pot. The chamber H is provided with an air inlet opening J controlled by a suitable damper as the slide damper K, the latter in the structure illustrated being ar- 45 ranged at the front of the stove above the fuel inlet. Preferably the upper wall L of the fuel inlet extends inwardly a slight dis- tance, and at this point the lower edge of the ring G is cut away, as indicated by M. An 50 opening or openings are provided for per- mitting the air to pass from the chamber H to the top of the fire pot, and I find it de- sirable to accomplish this by forming a plu- 55 rality of apertures N adjacent the lower edge of the ring.

In operation of the stove so far described,

fuel is supplied through the inlet E to the fire pot, the fuel burning within the fire-pot and the gases rising from the fuel in the fire-pot commingling with the air passing 60 from the chamber H through the apertures N. The amount of air entering the chamber H may be regulated by properly adjusting the slide damper, the burnt gases passing up through the drum and discharging by way 65 of the chimney flue O. Preferably the door P of the ash pit is provided with a damper Q so as to allow air to pass up through the grate R if desired. As the fuel fed to the fire-pot through the inlet opening tends to 70 shove the clinkers to the rear of the fire-pot, I have provided a novel construction of 75 grate which will allow the clinkers to be readily removed from the rear of the fire-pot. Thus as shown, the grating or bottom 80 R of the fire-pot is provided with a section S suitably mounted at the base of the fire-pot, and formed in its rear portion with an opening X, adapted to be closed by a section V preferably arranged below the plane of the 85 section S and mounted in bearings W so as to be moved forwardly to the position shown in dotted lines. Attached to the section V is an actuating portion or handle W' which extends to adjacent the door of the ash pit. 90 Thus by moving the section V forwardly the clinkers will be allowed to drop through the space X into the ash pit.

While I have shown and described the preferred form of the invention, I do not desire my protection limited to the exact de- 95 tails of construction illustrated, but consider my invention of sufficient scope to embody various modifications.

What I claim as my invention is:—

1. In an underfeed stove, the combination with a fire-pot, of a laterally-extending fuel inlet on the lower portion of said fire-pot, its lower wall inclining slightly upward and the outer edge thereof forming a fulcrum 100 for a poker adapted to lift the live fuel within said fire-pot to permit the feeding in of green fuel on to the grate, an air chamber adjacent to the upper wall of said laterally-extending fuel inlet, having inwardly-open- 105 ing air discharge apertures, and control means for admitting air into said air chamber.

2. In an underfeed stove, the combination with a fire-pot, of an annular member with- 110 in the upper portion of said fire-pot forming an air chamber with inward discharge open-

ings around the lower end thereof, and a laterally-extending fuel inlet on the lower portion of said fire-pot, its lower wall inclining slightly upward and the outer edge thereof forming a fulcrum for a poker adapted to lift the live fuel within said fire-pot to permit the feeding of green fuel on to the grate below the air inlet.

3. In a stove, the combination with a fire-pot and a drum thereabove, of an annular member within the upper portion of said fire-pot forming an air chamber having an external inlet and a series of inward discharge openings around the lower edge thereof, a laterally-extending fuel inlet con-

nexion on the lower portion of said fire-pot beneath said air chamber, its lower wall inclining slightly upward and the outer edge thereof forming a fulcrum for a poker adapted to lift the live fuel within the fire-pot to permit the feeding of green fuel thereunder, and a cover for the outer end of said fuel inlet. 20

In testimony whereof I affix my signature in presence of two witnesses.

WILLIAM V. ROBINSON.

Witnesses:

C. W. GREENWALD,
H. W. KAULITZ.
